DESIGN FOR A SKIRT AND JACKET ENSEMBLE

Mary Boyle, St. Louis, Mo.

Application March 25, 1941, Serial No. 99,834

Term of patent 3½ years

To all whom it may concern:

Be it known that I, Mary Boyle, a citizen of the United States, residing in the city of St. Louis, in the county of St. Louis, city and State of Missouri, have invented a new, original, and ornamental Design for a Skirt and Jacket Ensemble, of which the following is a specification, reference being had to the accompanying drawings, forming part thereof, in which—

I claim:

The ornamental design for a skirt and jacket ensemble, as shown.

MARY BOYLE.
